(57) **CLAIM**

The ornamental design for a solar powered outdoor light, as shown and described.

DESCRIPTION

FIG. 1 a front-right perspective view for a solar powered outdoor light, showing my new design;

FIG. 2 is a front elevational view of FIG. 1 thereof;

FIG. 3 is a rear elevational view of FIG. 1 thereof;

FIG. 4 is a right side elevational view of FIG. 1 thereof;

FIG. 5 is a left side elevational view of FIG. 1 thereof;

FIG. 6 is a top plan view of FIG. 1 thereof; and,

FIG. 7 is a bottom plan view of FIG. 1 thereof.

The broken line portion of the figure drawings is included to show portions of the article that forms no part of the claimed design.
